PROCESS AND APPARATUS FOR CONDITION-
ING COMMODITIES

Ralph Killingstad, New Smyrna, Fla., assignor, by
mesne assignments, to General American Pre-
cooling Corporation, Chicago, Ill., a corporation
of Delaware

Application June 27, 1936, Serial No. 87,796

6 Claims.

(Cl. 98—6)

This invention relates to the treatment of commodities, and more particularly has reference to the conditioning of commodities in a chamber. While the invention will be described with respect

5 to the conditioning of the load of freight cars, it will of course be appreciated that it is in no wise restricted thereto.

The present application is an improvement on application Serial No. 78,498, filed May 7, 1936, 10 by Frank J. Reilly.

The value of suitably conditioning commodities has long been recognized, but certain difficulties have been encountered, residing principally in the securing and maintaining of a 15 proper circulation of the conditioning agent. This is particularly true when the commodities are treated after loading in a car, and when the conditioning device is located outside of the car, for in such event there are problems which are 20 peculiar thereto.

One of the objects of this invention is to provide a process and apparatus for the conditioning of commodities.

Another object of this invention is to provide a 25 process and apparatus for insuring uniform distribution and passage of conditioned air throughout the entire contents of a freight car.

To accomplish the above and other important objects, this invention in general embraces the 30 idea of introducing air of the desired characteristics into a chamber containing the commodities to be treated, directing its path through such commodities, and withdrawing the air from the chamber so that the commodities will be effectively conditioned. In the preferred form, a substantially air-impervious cover is placed over the 35 commodities, the ends of such cover resting upon the commodities, and the central portion being raised above the top of the commodities. It is also preferable that the discharge opening for the air after passage through the commodities be located adjacent the central portion of the cover.

There is shown in the accompanying drawing one specific arrangement for carrying out the invention, but it will of course be understood that various modifications may be made therein without exceeding the scope of the inventive concept.

In the drawing, in which corresponding numerals refer to the same parts:

40 Figure 1 is a top plan view of a loaded freight car with a portion of the top of the car broken away.

Figure 2 is a sectional view taken along the line 2—2 of Figure 1.

45 This invention applies generally to the condi-

tioning of goods located in a chamber, but it finds particular application in the conditioning of produce that is located in a freight car preparatory to shipping.

In the drawing I have shown my invention as applied to the conditioning of the load of a freight car as mentioned above, and the numeral 1 indicates generally a freight car. This car may be either of the refrigerator type or of the plain box car type. In the drawing I have shown a conventional refrigerator car comprising a storage chamber 2 and ice bunkers 3. The bunker walls 4 may be of solid construction and provided with an upper opening 5 and lower opening 6, or they may be of the screen type.

15 Drain racks 7 may be provided in the bunkers to support the ice.

The invention may be practiced in a car that has been pre-iced, or not. Furthermore, the conditioning which will be hereinafter described, particularly if it is a cooling process, may be supplemented by filling the bunkers with ice prior to shipment, and likewise a top icing of the lading may be effected prior or subsequent to the conditioning.

20 The commodities that are to be shipped may be packed in baskets, lugs, boxes, crates, or other suitable container, depending of course upon the nature of the commodity. Such containers are shown diagrammatically in the drawing, and are indicated by the numeral 8. The lading is supported by racks 9, and is preferably so arranged as to provide longitudinal channels 11. In the drawing I have shown a normal loading of the products, and it will be appreciated of course that 25 a greater or lesser load may be placed in the car.

The usual doors 12 are provided in the center of the car, and in practicing the invention the doors on one side of the car are opened and there is inserted in the doorway a false door 13. As 30 best shown in Figure 1, the sides of the car 14 are considerably thicker than the false door 13, and the false door is so arranged in the doorway that its outer surface is flush with the outer surface of the car wall 14. A channel 13' is thereby formed 35 between the outer edge of the outside row of containers 8 and the inner surface of the false door 13. This channel of course extends the full depth of the commodities, and serves to facilitate the discharge of air from the car. The false door 13 is provided with an opening 15 in its top portion, and with an opening 16 near its base. As best 40 shown in Figure 2, with the normal loading of a freight car, the opening 15 will be above the top of the cover, to be later described, while the lower 45

opening 16 is below the cover as well as below the top of the load.

As indicated above, one of the problems in the conditioning of produce has been the necessity of securing and maintaining a proper distribution of the conditioned air throughout the mass of produce. To insure such adequate circulation and distribution, this invention embraces the use of a cover 17 which is preferably air-impervious. 5 The size of this cover may vary according to the particular type of operation, but it is usually desirable that it extend at least approximately one-third of the length of the lading, and, under most circumstances it is preferable, with a fully 10 loaded car, to carry the cover to within five or six feet of the bunker walls of a refrigerator car or the ends of a box car. As best shown in Figure 1, it is usually preferable to have the cover extend the full width of the car, although under certain 15 operating conditions this may be departed from. A lip 18 may be provided on the cover which extends into a duct 26, later to be described.

The principal feature of this invention resides in the specific arrangement of the cover 17. As 20 best shown in Figure 2, the ends of the cover rest upon the top of the load 8, and may be secured thereto by means of tacks 19. The central portion of the cover, however, is raised above the top of the load, and is supported in such raised 25 position by means of a box, crate or other suitable support 21. Preferably two boxes 21 are provided, one on each side of the top of the lading. It will therefore be seen that an air space is provided between the top of the load and the 30 cover which may serve as a channel for the passage of air. Also, when the conditioning is a cooling operation, the cover 17 will serve as a cooling 35 surface.

While the invention may be practiced with various 40 types of apparatus for conditioning the air introduced into the car, it finds particular application in combination with a portable conditioning unit which may be mounted upon an automobile truck and provided with the necessary 45 compressors, pumps and exhaust apparatus located in the section 22 of the chassis. Condensing elements 23 are mounted upon the truck which provide coils or other cooling elements in a diffusing element 24. The diffuser is provided 50 with a mouth 25 which supports a duct 26 extending to and secured in the opening 15 of the false door. A similar duct (not shown) extends from the lower part of the diffuser to the opening 16 of the false door. Both of the ducts are 55 preferably flexible and airtight. One of the ducts serves to convey air from the car to the diffuser 24, while the other duct serves to convey the air so conditioned in the diffuser back to the car.

Of course, it would be possible to introduce the 60 air through either one of the openings 15 or 16 of the false door and withdraw it from the other opening, but it is decidedly preferable to introduce the air through the opening 15 and withdraw air from the car through opening 16. By such a 65 process the air is withdrawn through opening 16 and its corresponding duct, then passes through the diffuser 24 where it is conditioned and then such conditioned air is passed through the duct 26 and opening 15 into the interior of the car. 70 By "conditioning" is meant cooling, heating, hydrating, dehydrating, cleaning, or any other desired treatment.

The presence of the cover 17 of course prevents the entrance of the air immediately into 75 the top of the load adjacent the door, and also

prevents the passage of such air immediately into the channel 13'. In other words, the cover 17 prevents short circuiting and permits the incoming air to enter the produce only adjacent the ends of the car. It is also to be noted that 5 the stream of incoming air strikes the opposite side of the car or rather the closed door on the opposite side, and thus facilitates a uniform and substantially equal passage of the air toward the opposite ends. 10

When the air reaches that portion of the load over which the cover 17 does not extend, it passes downwardly into the load, as indicated by the arrows 21. The longitudinal channels 11 between the commodity containers afford a particularly 15 effective passageway for the air as it passes toward the center of the car and thence to the discharge opening 16. The major portion of the air travels an appreciable distance through the commodity and through the channels 11, but 20 some of the air begins to ascend from the channels as soon as it passes underneath the cover 17, as indicated by the arrows. When the air, both 25 within the commodity and channels, and also the air intermediate the cover and top of the 30 commodity, reaches the center of the car, it passes transversely toward the false door, and thence 35 downwardly through the channel 13' between the false door and the commodity containers to the discharge opening 16. 30

It is obvious that the channels 11 facilitate the passage of the air lengthwise of the car, and, while most forms of containers 8 are so constructed as to permit the passage of air transversely therethrough, the space between the cover 17 and the top of the commodity affords a ready transverse channel for said air as can not pass transversely through the containers. 35

The advantages of this invention are believed 40 to be apparent. The air is usually introduced about the rate of twelve thousand cubic feet a minute, and the incoming stream, immediately after admission to the car, is broken up by impacting the opposite car side. There is of course no impedance to the uniform distribution of air 45 in the space above the load and above the cover, and consequently substantially equal amounts of air pass to the respective ends of the car. In order to enter the load, the air must pass into the commodities at the ends of the car and 50 especially into the longitudinal channel 11. The major part of the air passes through the channels and commodity to the center of the car, at which point it passes upwardly into the space between the raised cover and the load. It will be seen 55 that in this way an effective cooling of the entire contents is possible, and furthermore the egress of air from the car is facilitated by the air space between the raised cover and the load and also the channel 13' formed between the false door 60 and the load.

While there is shown and described the preferred embodiment of this invention, it is to be understood that this is exemplary merely, and that the inventive concept is to be determined 65 solely by the scope of the appended claims.

I claim:

1. A method of conditioning the contents of a chamber comprising introducing a stream of conditioned air at a point in the chamber above the 70 contents, directing such stream into the contents at a point remote from its entrance into the chamber while preventing its contacting the contents when passing from the first to the second point, then passing the air through the contents, 75

and exhausting the air from the chamber by causing the stream to pass upwardly out of the contents and thence to a discharge opening from the chamber below the top of the contents.

5. 2. A method of conditioning the contents of a chamber comprising introducing a stream of conditioned air at a point in the chamber above the contents, directing such stream into the contents at a point remote from its entrance into the chamber while preventing its contacting the contents when passing from the first to the second point, then passing the air through the contents, and exhausting the air from the chamber by causing the stream to pass upwardly out of the contents and thence to a discharge opening from the chamber immediately below the point of admission to the chamber and below the top of the contents.

20 3. A method of conditioning the contents of a chamber comprising introducing a stream of conditioned air into the chamber at a point intermediate the ends thereof, directing such air towards the ends of the chamber and out of contact with the contents, then introducing the air to 25 the contents in the vicinity of the ends and passing it toward the center of the chamber, and exhausting the air from the chamber by causing the stream to pass upwardly out of the contents and thence to a discharge opening from the 30 chamber.

4. A method of conditioning the load of a freight car comprising withdrawing air from the center of the car at a point beneath the load level, conditioning the air exterior of the car, 35 introducing the conditioned air to the center of the car through one side thereof and above the load level, directing the air against the opposite side of the car, passing the air into the top of the load adjacent the ends of the car only, then 40 passing the air through the load, and withdrawing the air by causing the same to pass upwardly

out of the load and thence to the point of discharge from the chamber.

5. In an air-conditioning apparatus for the load of a freight car, a door at the center of the car provided with an aperture above the normal load level and an aperture below the normal load level, a member extending longitudinally from the center of the car and covering at least approximately one-third of the load, the ends of said member being secured to the top of the load 10 and the central portion thereof being raised above the load, said member adapted to substantially prevent the passage of air therethrough, an air-cooling unit located exteriorly of the car, means to convey cooled air from the 15 unit through the upper aperture of the door above the said member, and means to convey air from the car to the unit, said last mentioned means extending from the lower aperture in the door below said member. 20

6. An apparatus for conditioning the load of a freight car comprising a door at the center of the car provided with an aperture above the normal load level and an aperture below the normal load level, said door being of a thickness less than 25 that of the car wall and having its outer surface flush with the outer surface of the car wall, a member extending longitudinally from the center of the car and covering at least approximately one-third of the load, the ends of said member 30 being secured to the top of the load and the central portion being raised above the top of the load, said member adapted to substantially prevent the passage of air therethrough, an air-cooling unit located exteriorly of the car, means 35 to convey cooled air from the unit through the upper aperture of the door above the said member, and means to convey air from the car to the unit, said last mentioned means extending from the lower aperture in the door below said member. 40

RALPH KILLINGSTAD.
